UNITED STATES PATENT OFFICE.

THOMAS C. CAREY, OF TRENTON, NEW JERSEY, ASSIGNOR TO JACOB C. BLOOM AND JOHN F. GODLEY, OF TRENTON, NEW JERSEY.

BED-SPRING.

No. 802,624.

Specification of Letters Patent.

Patented Oct. 24, 1905.

Application filed December 17, 1904. Serial No. 237,287.

To all whom it may concern:

Be it known that I, THOMAS C. CAREY, a citizen of the United States, residing at Trenton, in the county of Mercer and State of New Jersey, have invented certain new and useful Improvements in Bed-Springs, of which the following is a specification.

This invention embodies improvements in spring-cushions, and in the preferred adaptation thereof involves a peculiar construction of bed-spring.

The invention aims to provide a spring-cushion of this type which is made wholly of metal and which is constructed with reference primarily to secure a maximum degree of simplicity in order that the device may be manufactured as cheaply as possible.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment thereof is shown in the accompanying drawings, in which—

Figure 1 is a top plan view of a bed-spring embodying the essential features of the invention. Fig. 2 is a bottom plan view of the invention, a few only of the helical springs of the device being illustrated, as in Fig. 1. Fig. 3 is a sectional view, partially broken away, taken about on the line X-X of Fig. 1, looking in the direction of the arrow. Fig. 4 is a broken perspective view of a corner portion of the device embodying the invention, showing more clearly the manner of interlocking the spring-supporting wires. Fig. 5 is a longitudinal sectional view.

Corresponding and like parts are referred to in the following description and indicated in all the views of the drawings by the same reference characters.

The general structure of the spring-cushion which comprises this invention is substantially the same as many of those now in use, which embody a suitable supporting-frame, ordinarily of metal, and a sufficient number of helical springs supported in said frame and adapted to sustain any weight disposed upon

the device. The common defect in many bed-springs now in use is due to the fact that the weight of the springs, together with any weight disposed thereon, is carried partially by the side rails of the bed between the ends thereof. It is therefore an object of this invention to provide a construction which will cause all weight to be sustained at the corner portions of the bed, thereby obviating likelihood of sagging of the side rails or causing inward and outward movement of the head and foot pieces of the bedstead.

Specifically describing the cushion, the same consists, essentially, of a suitable supporting-frame, which for the purpose of this description embodies side rails 1 and end rails 2. The side rails 1 are preferably made of substantial tubing, angle-iron, or the like, the ends of which are received in socket members 3, secured adjacent the end portions of the rails 2. The end rails 2 are preferably made of angle-bars to give the necessary rigidity, and the socket members 3 are secured to one of the wings of said angle-bars by bolts or suitable fastenings, preferably. The side rails 1 of the frame are braced and connected at intervals in the length thereof by means of transverse bars 4, which bars are preferably of flat metal formation, with the end portions thereof bent at an angle, as shown at 5, and curved, as shown at 6. The curved portions of the bars 4 extend over or receive the side rails, being firmly secured thereto by means of rivets 7 or the like. The provision of the members 5 of the bars 4 disposes said bars some distance below the side rails, as shown most clearly in Fig. 5 of the drawings. The several supporting-bars 4 are connected by a plurality of braces 8, which are made of flat metal pieces having the end portions thereof turned at an angle and attached to the bars 4 at points between said bars. The braces 8 are arranged longitudinally of the frame or parallel with the side rails 1.

Supporting-bars 4 are utilized to support the usual helical springs 9, customarily used in spring-cushion construction, the lower extremities of said springs being passed through openings in the bars 4, and thereby engaged therewith. The edge portions of the bars 4 are turned upwardly, because of the manner of construction of the end portions thereof, the springs 9 thus bearing against said edge portions in a manner readily noted. The

lower ends of the springs 9 are thus supported by the bars 4, the upper ends of said springs, however, being held in proper position by means of a plurality of longitudinal 5 transverse supporting strips or wires. The longitudinal supporting-wires 10 are connected to the end rails 2 of the frame by flexible connections in the form of coil-springs 11. The longitudinal wires 10, as well as the trans- 10 verse wires 12, are crimped throughout their length, and the wires 10 are of peculiar formation, being doubled at a point between the ends thereof to form spaced lengths which interlock with the uppermost volute of each 15 of the springs 9 aforesaid. The point at which the wires 10 are bent upon themselves is engaged by one end of an adjacent spring 11, as shown at 11^a, the extremities of the wires 10 being bent to form hooks with each 20 of the springs at the opposite end of the frame engaged. The longitudinal wires 10 are thus held taut by the connection 11 aforesaid. However, it will be noted that said wires are not rigid, but have a flexible or spring 25 movement under the usual conditions of service. One of the spaced elements of each of the longitudinal wires 10 passes beneath the uppermost volute of the line of springs with which said wire coöperates, whereas the ad- 30 jacent elements pass above said volute, there- by affording a more positive interlocking connection between the springs and spaced mem- bers of the wires 10. The ends of the springs 11 opposite those connected with the wires 35 10 pass through suitable openings lengthwise of the end rails 2, affording the necessary connection with these parts. Connecting each end of the end rails 2 is a longitudinal truss- 40 wire 13, connecting the springs 11, which lat- ter are also connected with the end rails in the same manner as are the springs with which the wires 10 coöperate. The longitudinal truss-wires 13 form flexible connections and have the end portions of the transverse 45 supporting-wires 12 connected therewith, said wires 12 being hooked around the wires 13 in any suitable manner. The transverse brace-wires coöperate with the springs 9, pass- 50 ing beneath and above opposite portions of the uppermost volute of each of the springs in transverse alignment therewith. At the same time the transverse wires 12 pass above the element of the wire 10, which passes over the uppermost volute adjacent the springs 9 55 and from thence beneath the adjacent spaced element of such wire, this construction being such that the longitudinal and transverse supporting-wires 10 and 12, respectively, are pec- 60 cularly interlocked with each other and at the same time are firmly attached to the up- 65 permost volute of each of the springs 9 with which said wires engage. The longitudinal wires 10 are always under tension because of the provision of the flexible connections 11, and the peculiar interlocking connection of

said wires 10 and of the wires 12 is such that the springs 9 are held firmly in proper position.

It will be noted that certain of the helical springs 9 are disposed above the side rails 1 70 of the frame of the cushion, and these portions are attached to the said side rails by the same fastenings which secure the curved portions 6 of the supporting-bars 4 to said rails 1. The lower extremities of the side springs 75 9, in other words, are firmly riveted to said side rails, the above producing a substantial reinforced edge portion for the cushion and causing the whole weight of the springs to be sustained by the side rails above mentioned. 80

The end rails 2 project some distance beyond the side rails 1 at the extremities thereof, the above construction being such that the ends of the rails 2 will rest upon the bedstead at the corners thereof, disposing all strain at 85 this point instead of along the side rails of said bedstead. The foregoing gives rise to advantages which have been more clearly pointed out hereinbefore. Transverse wires at the ends of the cushion-frame are used to 90 reinforce the connections 11, being connected at terminals with end springs and passing through the intermediate springs 11 at a point between the ends of the latter.

Having thus described the invention, what 95 is claimed as new is—

1. In a spring-cushion, the combination of a frame, supports connecting sides of the frame, helical springs connected at one end with the said supports, supporting-wires connected with the opposite ends of the helical springs, springs connecting said supporting-wires with the frame, and wires connecting the last-mentioned springs at points between the ends thereof. 105

2. In a spring-cushion, the combination of a frame comprising sides and ends having the terminals of the latter extending beyond the said sides, flexible connections between the extended terminals of the ends of the frame, helical springs mounted in the frame, and strips engaging said helical springs and connected with the flexible connections. 110

3. In a spring-cushion, the combination of a frame comprising sides and ends, the ends having the terminals thereof extended beyond the said sides, flexible connections between the extended end portions of the frame and comprising longitudinal truss-wires, and springs connecting the ends of the truss-wires with the extended terminals of the ends of the frame, helical springs mounted in the frame, and transverse supporting-wires engaging the helical springs and connected at the extremities thereof with the flexible connections afore- 115 said. 120

4. In a spring-cushion, the combination of a frame comprising sides and ends, the ends having the terminals thereof extended beyond the said sides, flexible connections between the 125 130

extended end portions of the frame and comprising longitudinal truss-wires, springs connecting the ends of the truss-wires with the extended terminals of the ends of the frame, 5 helical springs mounted in the frame, transverse supporting-wires engaging the helical springs and connected at the extremities thereof with the flexible connections aforesaid, longitudinal wires engaging the helical springs, 10 springs connecting the ends of said longitudinal wires with the ends of the frame, and transverse reinforcing-wires connecting the springs by which the longitudinal truss-wires and supporting-wires are connected with the 15 frame.

5. In a spring-cushion, the combination of a frame composed of sides and ends, supports connecting the sides, rows of springs mounted at one end upon said supports, supporting- 20 wires connected with ends of the frame and engaging the opposite end portions of longitudinal rows of said springs, and other supporting-wires arranged transverse to the first-mentioned supporting-wires and connecting 25 transverse rows of the springs aforesaid.

6. In a spring-cushion, the combination of a frame composed of sides and ends, supports connecting the sides, a plurality of helical springs mounted at one end upon said sup- 30 ports, supporting-wires engaging opposite end portions of said springs, springs connecting said supporting-wires with ends of the frame, and other supporting-wires arranged transverse to the first-mentioned supporting- 35 wires and engaging the helical springs and the first-mentioned supporting-wires, as specified.

7. In a spring-cushion, the combination of a frame composed of sides and ends, support- 40 ing-bars mounted in the frame, springs disposed upon said bars, supporting-wires flexibly connected at the ends thereof with ends of the frame and engaging the springs aforesaid, and other supporting-wires connecting the 45 springs and arranged transverse to the first-mentioned wires and flexibly connected with the frame.

8. In a spring-cushion, the combination of a frame composed of sides and ends, support- 50 ing-bars in said frame, springs attached at one end to the supporting-bars aforesaid, and supporting-wires engaging the opposite end portions of longitudinal rows of said springs and flexibly connected at their ends with ends 5 of the frame, said supporting-wires comprising spaced elements.

9. In a spring-cushion, the combination of a frame composed of sides and ends, support- 55 ing-bars in said frame, springs attached at one end to the supporting-bars aforesaid, sup- 60 porting-wires engaging the opposite end portions of said springs and flexibly connected at

their ends with ends of the frame, said sup- 65 porting-wires comprising spaced elements, truss-wires connecting end portions of the ends of the frame, and supporting-wires arranged transversely to the first-mentioned supporting-wires, and connected at their ends with the truss-wires mentioned.

10. In a spring-cushion, the combination of 70 a frame composed of sides, bars connecting opposite sides of the frame, springs connected at one end with the bars, and supporting-wires engaging the opposite end portions of the springs and doubled upon themselves to 75 form spaced elements.

11. In a spring-cushion, the combination of 80 a frame composed of sides and ends, bars connecting opposite sides of the frame, springs connected at one end with the bars, support- 85 ing-wires engaging the opposite ends of the frame and doubled upon themselves to form spaced elements, and springs connecting the doubled supporting-wires to the ends of the frame. 85

12. In a spring-cushion, the combination of a frame composed of sides and ends, supports connecting the sides, a plurality of helical springs mounted at one end upon said supports, supporting-wires engaging opposite 90 end portions of said springs, other springs connecting said supporting-wires with ends of the frame, other supporting-wires arranged transverse to the first-mentioned supporting- 95 wires and engaging the helical springs and the first-mentioned supporting-wires, as specified, and means for flexibly connecting the transverse supporting-wires with the frame.

13. In a spring-cushion, a frame having terminal portions of opposite bars extended be- 100 yond the proximal connecting-bar, a connect- 105 ed series of helical springs mounted upon said connecting-bar to provide a reinforced edge, and a flexible connection attached at its ex- tremities to the aforesaid extended terminal portions of opposite frame-bars and joined to the cushion-reinforcing springs.

14. In a spring-cushion, the combination of 110 a frame, a series of helical springs mounted in the frame, longitudinal supporting-wires interlaced with the helical springs, springs connecting the ends of the longitudinal sup- 115 porting-wires with the frame, transverse sup- porting-wires interlaced with the helical springs, and flexible connections between the ends of the frame connected with the terminals of the transverse supporting-wires afore- said.

In testimony whereof I affix my signature in presence of two witnesses.
